Fig. 7

FIGURE 1 is a side elevation of a machine tool base and bed unit showing my new design, the opposite side being a mirror image thereof;

FIGURE 2 is a top plan view thereof;

FIGURE 3 is an end elevation, the opposite being a mirror image thereof;

FIGURE 4 is an end elevation of the inner end of either of the base elements thereof;

FIGURE 5 is a side elevation of a modified form of the machine tool base and bed unit shown in FIGURE 1, the undisclosed inner end of the base being similar to the base shown in FIGURE 4;

FIGURE 6 is a top plan view thereof; and

FIGURE 7 is an end elevation thereof, the opposite end being a mirror image thereof.

The dominant features of my design reside in the portions shown in full lines.

This is a division of design application Serial No. D.79,759, filed April 30, 1964, and now Patent No. D.204,207.

I claim:

The ornamental design for a machine tool base and bed unit, as shown and described.
